United States Patent Office

Des. 190,534
Patented June 6, 1961

190,534

AIRPLANE

Henry A. Smolinski, 7860 Mesa Drive,
Santa Susana Heights, Calif.

Filed Mar. 28, 1960, Ser. No. 59,894

Term of patent 14 years

(Cl. D71—1)

Fig. 2

Fig. 3

Fig. 4

Fig. 5

FIGURE 1 is a perspective view of an airplane showing my new design, taken from above and one side;

FIGURE 2 is a front elevation thereof;

FIGURE 3 is a top plan view thereof;

FIGURE 4 is a side elevation of the airplane; and

FIGURE 5 is a rear elevation thereof.

I claim:

The ornamental design for an airplane, substantially as shown.
